CHAIR

Richard M. Chapin, Charlotte, N.C., assignor to Dolly
Madison Industries, Huntingburg, Ind.

Filed Jan. 7, 1972, Ser. No. 216,335

Term of patent 7 years

Int. Cl. D6—01

U.S. Cl. D6—75

The figure is a front perspective view of a chair showing my new design. The back of the chair, not shown in the drawing, is substantially plain and unornamented.

I claim:

The ornamental design for a chair, substantially as shown and described.
